(57) **CLAIM**

The ornamental design for a leaf-themed container lid, as shown and described.

DESCRIPTION

FIG. 1 is a front perspective view of a first embodiment of a leaf-themed container lid, showing the new design;

FIG. 2 is a front view thereof;
FIG. 3 is a rear view thereof;
FIG. 4 is a side view thereof;
FIG. 5 is the opposite side view thereof;
FIG. 6 is a top plan view thereof;
FIG. 7 is a bottom view thereof;
FIG. 8 is a front perspective view of a second embodiment thereof;

FIG. 9 is a front view thereof;
FIG. 10 is a rear view thereof;
FIG. 11 is a side view thereof;
FIG. 12 is the opposite side view thereof;
FIG. 13 is a top plan view thereof;
FIG. 14 is a bottom view thereof;
FIG. 15 is a front perspective view of a third embodiment thereof;

FIG. 16 is a front view thereof;
FIG. 17 is a rear view thereof;
FIG. 18 is a side view thereof;
FIG. 19 is the opposite side view thereof;
FIG. 20 is a top plan view thereof;
FIG. 21 is a bottom view thereof;
FIG. 22 is a front perspective view of a fourth embodiment thereof;

FIG. 23 is a front view thereof;
FIG. 24 is a rear view thereof;
FIG. 25 is a side view thereof;
FIG. 26 is the opposite side view thereof;
FIG. 27 is a top plan view thereof;
FIG. 28 is a bottom view thereof;
FIG. 29 is a front perspective view of a fifth embodiment thereof;

FIG. 30 is a front view thereof;
FIG. 31 is a rear view thereof;
FIG. 32 is a side view thereof;
FIG. 33 is the opposite side view thereof;
FIG. 34 is a top plan view thereof;
FIG. 35 is a bottom view thereof;
FIG. 36 is a front perspective view of a sixth embodiment thereof;

FIG. 37 is a front view thereof;
FIG. 38 is a rear view thereof;
FIG. 39 is a side view thereof;
FIG. 40 is the opposite side view thereof;

(Continued)

FIG. 41 is a top plan view thereof; and,
 FIG. 42 is a bottom view thereof.
 In all figures, the broken lines showing the environmental
 subject matter and/or portions of the lid are included for
 illustrative purposes and form no part of the claimed design.
